UNITED STATES PATENT OFFICE.

JOHN H. GOULD, OF PLYMOUTH, ILLINOIS, ASSIGNOR TO ALFRED C. STEWART, OF LOS ANGELES, CALIFORNIA.

CARBURETER.

1,050,059.

Specification of Letters Patent.

Patented Jan. 7, 1913.

Application filed May 26, 1909. Serial No. 498,523.

To all whom it may concern:

Be it known that I, JOHN H. GOULD, a citizen of the United States, residing at Plymouth, in the county of Hancock and 5 State of Illinois, have invented a new and useful Improvement in Carbureters, of which the following is a specification.

This invention relates more particularly to that type of carbureters for internal combustion engines in which the supply of the explosive mixture to the engine is automatically regulated in accordance with the needs of the engine by a device which is operated by the suction of the engine.

15 The objects of the invention are to produce an efficient carbureter of very simple and practical construction, in which the feed of both the air and the fuel or hydrocarbon are automatically regulated in accordance 20 with the speed of the engine, whereby a mixture of the proper proportion of air and the volatilized fuel is supplied to the engine at all speeds thereof; also to so construct the carbureter that the air and fuel- 25 regulating valves or devices are combined in a single movable unit or part without intermediate joints or connections, thereby greatly simplifying the construction of the carbureter and reducing the number of its 30 working parts; also to provide an air-regulating valve which is operated automatically by the suction of the engine and has a fuel supply passage through which the fuel is drawn by the suction of the air past the 35 valve; and also to improve carbureters of this type in the respects hereinafter described and set forth in the claims.

In the accompanying drawings, consisting 40 of two sheets: Figure 1 is a sectional elevation of a carbureter embodying the invention. Fig. 2 is a plan view thereof. Fig. 3 is a sectional plan thereof in line 3—3, Fig. 1. Fig. 4 is a side elevation thereof. Fig. 45 5 is a fragmentary sectional elevation of a carbureter of slightly modified construction.

Like reference characters refer to like parts in the several figures.

Gasolene is the fuel ordinarily used in 50 the carbureter and the term "gasolene" alone will be employed in this specification for the sake of brevity, without, however, intending thereby to restrict the use of the carbureter to this particular fuel.

55 A represents a gasolene chamber, B an air and gasolene mixing chamber, and C air

inlet openings in the carbureter casing between gasolene and mixing chambers. The casing conveniently consists of a lower section α which forms the gasolene chamber A, an intermediate section α' which has a detachable screw connection with the top of the lower section, and an upper section α'' which is connected by a screw coupling α'' to the intermediate section. The intermediate section α' has a reduced waist portion 60 which forms a seat α^4 for the air admission and charge regulating valve, the air inlet openings C being provided in this section below the valve seat α^4 . The portion of this section above the valve seat α^4 flares or increases in diameter upwardly and together with the upper section α'' of the casing forms the mixing chamber B. The described construction of the casing is desirable, but the casing could be of any other suitable construction. The pipe leading to the engine is attached to the upper end of the casing and communicates with the mixing chamber through a discharge or outlet passage D, which is controlled by a throttle valve d of 70 75 80 any usual or suitable construction.

E represents the combined air admission and charge regulating valve which is arranged to move vertically in the mixing chamber and, when inactive, to rest on the 85 seat α^4 formed by the reduced waist of the intermediate section of the casing. This seat and the coöperating face of the valve are preferably tapered or frusto-conical in shape. The valve has a stem e which depends into the gasolene chamber A, through a guide bearing e' in the latter, and is hollow or is provided with a passage e^2 which connects with one or more discharge ducts e^3 leading through the body of the valve to 90 the periphery thereof, preferably to the face thereof which rests on the valve seat. When the valve is seated it cuts off the admission of air through the inlet openings C to the mixing chamber and also closes the gasolene ducts e^3 so as to cut off the mixing chamber from the gasolene chamber. The valve E is 95 lifted off of its seat by the suction of the engine when the latter is working, and air is thus admitted into the mixing chamber. 100

The gasolene is sucked up from the gasolene chamber through the passage e^2 and discharge ducts e^3 by the flow of the air around the valve past the ducts e^3 , and is 105 mingled with the air in the mixing chamber 110.

to produce the explosive mixture. The valve and its hollow stem thus in effect constitute a gasoline spray or supply nozzle. The valve is lifted off of its seat more or less and admits a greater or less volume of air, depending upon the speed and consequent suction of the engine, and in order to proportionately vary the feed of the gasoline so as to insure a mixture of proper richness at all times, a relatively stationary needle valve F is arranged in the passage e² of the gasoline nozzle and this passage is made tapering. This gasoline valve F obstructs the nozzle less or more and consequently admits more or less gasoline to the mixing chamber accordingly as the automatic valve is moved farther from or nearer to its seat to increase or decrease the supply of air. The gasoline valve F has a screw-threaded shank f which passes through a nut f' in the bottom of the gasoline chamber A and is provided at its outer end with a handle for turning it to initially adjust the valve as may be necessary to properly regulate the feed of the gasoline. If desired, the gasoline valve F can be connected to its shank f by a universal joint f², as shown in Fig. 5, to make the valve self-centering in the nozzle.

By the described construction and arrangement of the automatic valve, the air is drawn past the valve, immediately around the gasoline discharge orifices thereof, regardless of the position of the valve, which insures an adequate supply of the gasoline to the air under the varying suction produced by the engine.

The automatic valve is preferably made of such weight that it will maintain a suitable velocity of air past it and past the fuel ducts to insure a uniform mixture and steady action of the engine and to seat itself without the use of a spring. In operation, for any given demand of the engine, the valve will automatically lift sufficiently to give the engine the requisite charge, *i. e.*, until the pressure above it plus its own weight, will approximately equal the atmospheric pressure below it.

In the construction shown in Figs. 1 and 3, the valve stem e is provided with external helical threads G and the guide bearing e' in which it works is correspondingly threaded, which causes the valve to rotate in its up and down movements, thus making its movements steady and gradual and preventing a jerky action thereof. If preferred, however, the valve stem and its guide can be made smooth, as shown in Fig. 5, and any suitable means for dampening or checking the movements of the valve can be employed.

H represents a valve operated by a float I and controlling the supply of gasoline to the carbureter for keeping it at a constant level in the gasoline chamber A. In

the construction shown, the float is annular and located in the gasoline chamber A surrounding the gasoline nozzle, but this construction is not essential and the float could be arranged in a separate float chamber 70 communicating with the chamber containing the nozzle, as in some makes of carbureters.

I claim as my invention:

1. In a carbureter for internal combustion engines, the combination of a casing having an air inlet, an automatic valve whose position is dependent upon the demands of the engine and which controls the admission of all air to the carbureter, 75 said valve having a fixed stem provided with a gasoline supply passage, and a valve which co-operates with said passage for regulating the supply of gasoline in proportion to the supply of air for mixture with the 85 air, substantially as set forth.

2. In a carbureter for internal combustion engines, the combination of a casing having an air inlet and a valve seat, a valve which is operated automatically by the suction of the engine and co-operates with said seat to control the admission of air to the carbureter, said valve having a fixed hollow stem provided with a passage for the gasoline and one or more ducts leading from 95 said passage to the periphery of the valve adjacent to the valve seat, and a valve which co-operates with said hollow stem of the automatic valve to regulate the supply of gasoline in proportion to the supply of air 100 for mixture with the air, substantially as set forth.

3. In a carbureter for internal combustion engines, the combination of a casing having an air inlet and a valve seat, a 105 weighted valve which is operated automatically by the suction of the engine and co-operates with said seat to control the admission of air to the carbureter, said valve having a fixed stem provided with a tapering passage for the gasoline and one or more ducts leading from said passage to the periphery of the valve adjacent to the valve seat, and an adjustable needle valve 115 extending into the tapering passage of said stem of the automatic valve to regulate the supply of gasoline for mixture with the air, substantially as set forth.

4. In a carbureter for internal combustion engines, the combination of a casing having a valve seat, an air inlet opening in the wall of the casing at one side of said seat, and a carbureting chamber at the opposite side of said valve seat having walls which diverge away from said valve seat, an automatic valve whose position is dependent upon the demands of the engine and which co-operates with said seat to control the admission of air to the carbureter, gasoline supply ducts being provided which have dis- 130

charge openings in immediate proximity to the peripheral portion of said valve seat which coöperates with said valve, a valve which controls the supply of gasolene to 5 said ducts and comprises a part having a passage and a needle located in said passage, one of which parts is tapered, one part of said gasolene supply valve being fixed to and moving with said air valve for maintaining the supply of gasolene through said 10 ducts proportional to the supply of air throughout the movement of said valve for mixture with the air, substantially as set forth.

15 5. In a carbureter for internal combustion engines, the combination of a mixing chamber, a gasolene chamber, a valve which is operated automatically by the engine suction and controls the admission of air to 20 the mixing chamber, said valve having a stem with a tapering gasolene passage entering the gasolene chamber and a connecting discharge duct, and an adjustable stationary valve coöperating with the walls of 25 said tapering passage, whereby the opening between said passage and said valve increases with the suction on said automatic

valve for regulating the feed of the gasolene, substantially as set forth.

6. In a carbureter, the combination of 30 a casing having a gasolene chamber, a carbureting chamber above said gasolene chamber and an air inlet between said chambers, and a valve seat between said air inlet and said carbureting chamber, a vertically movable valve which is operated automatically by the engine suction and coöperates with 35 said seat to control the passage of air to said carbureting chamber, said valve having a fixed stem with a gasolene passage depending into the gasolene chamber and a connecting discharge duct leading to the periphery of said valve adjacent to said valve seat, and a relatively stationary valve in said 40 passage in the valve stem and coöperating with the walls thereof for regulating the feed of the gasolene, substantially as set forth.

Witness my hand, this 22d day of May, 1909.

JOHN H. GOULD.
